UNITED STATES PATENT OFFICE.

NORMAN MARSHALL, OF NEWTON, MASSACHUSETTS.

INCANDESCENT-LAMP SOCKET.

No. 811,161.

Specification of Letters Patent.

Patented Jan. 30, 1906.

Application filed March 31, 1904. Serial No. 200,974.

To all whom it may concern:

Be it known that I, NORMAN MARSHALL, of Newton, in the county of Middlesex and State of Massachusetts, have invented certain new and useful Improvements in Incandescent-Lamp Sockets, of which the following is a specification.

The invention relates to shells or casings for incandescent-lamp sockets, and more especially to the means for detachably connecting the parts of the shell together.

Incandescent-lamp sockets as commonly constructed are provided with an outer metallic shell or casing which surrounds and supports the insulating and current-carrying parts. This casing consists of a cylindrical part open at the ends, which is called the "shell," and a cap which closes one end of the shell and forms the means for connecting the socket to a fixture and supporting the parts of the socket. The shell and cap are so connected together that they may be readily separated or secured together in assembling, wiring, or inspecting the socket. These parts are commonly formed of thin sheet metal, and devices heretofore commonly used for detachably connecting them together have required the use of separate or additional pieces of metal secured to or in the cap or shell to reinforce the thin metal for the reception of the screws or other securing devices or to form a part of such devices.

In practicing my invention I form integral lugs in the cap or shell by drawing the thin metal radially inward or outward at the points where the lugs are to be formed and also form coöperating slots or recesses in the other part of the casing, which register with the lugs when the cap and shell are brought together. I have found that an integral lug may be formed in the thin metal of sufficient strength and rigidity to form one member of an efficient connecting device by drawing the metal radially inward or outward. I have also found that the metal may be thus drawn without injury to the shell (or cap) and without destroying the temper and resiliency of the shell (or cap) by a local application of heat to the part to be drawn before or during the drawing.

In the drawings I have shown a socket-casing in which I have embodied the invention.

In the drawings, Figure 1 shows the parts of a socket-casing in elevation upon a somewhat enlarged scale, the parts being disconnected and the thickness of the metal being exaggerated for the sake of clearness. Fig.

2 is a view looking toward the left in Fig. 1, showing the parts of the casing assembled. Fig. 3 is a horizontal section on line 3 3, Fig. 1. Fig. 4 is a section on line 4 4, Fig. 2. Fig. 5 is a vertical section on line 5 5, Fig. 1.

In the socket-casing shown in the drawings, A indicates the cylindrical metallic shell, and B the cap, which is provided with a cylindrical portion B', adapted to fit over the end 65 of the shell A, the cap and shell forming the two telescoping parts of the casing. The connecting devices are formed in the overlapping parts of the shell and cap. In the casing shown two forms of connecting devices 70 are employed, and there are two sets of devices of each form. In one form of connecting devices shown the cap B is provided with a lug C, formed by drawing a portion of the shell radially inward. This lug coöperates 75 with a longitudinal slot D and a transverse slot D', formed in the shell A. The slot D' extends transversely from the slot D, and the two slots open into each other. There are two of this form of connecting device arranged on diametrically opposite sides of the casing. In the other form of connecting devices the cap B is provided with a lug E, formed by drawing the metal of the cap radially inward. This lug coöperates with a 80 longitudinal slot F and a transversely arranged hole, slot, or recess F', formed in the shell. In this form of connection the recess 85 F' is separated from the longitudinal slot F by a section A' of the shell, so that the lug E' 90 and recess F' form a locking device for preventing relative turning of the parts.

In connecting the parts together the cap B is applied to the shell A, with the longitudinal slots D and F in register with the lugs C 95 and E, so that as the shell passes into the cap the lugs pass into the longitudinal slots and into alignment with the transverse slots. The parts are then rotated relatively to each other. As the parts are rotated the lugs C enter the transverse slots D', locking the parts together against longitudinal movement. At the same time the lugs E act against the parts A' of the shell A, which separates the recesses F from the slots F', springing the shell inward at 100 these points sufficiently to allow the lugs E to enter the slots F'. As soon as the lugs E have passed into the slots F the shell springs back. The shoulders F² now coöperate with the lug E to prevent rotation of the parts 105 with relation to each other in either direction until sufficient force is applied to cause the

lug E to spring the shell inward. The lugs E and recesses F therefore act as spring locking devices to prevent relative rotation of the parts, as well as longitudinal movement 5 with relation to each other.

In drawing the metal of the shell or cap radially to form the lugs E, I prefer to shear through the metal on transverse parallel lines E' and to draw the metal radially either 10 inward or outward between the lines. The lugs thus formed are integral with the shell or cap at their ends and are provided with sides extending transversely and at right angles to the periphery of the shell or cap, 15 which will effectively coöperate with the transverse sides of the slots F' in securely connecting the parts together. The ends of the lugs may also be readily formed to act as cams for springing the shell inward to allow 20 the passage of the lug into or out of the slot F'.

The shearing through the metal on parallel lines may be done before or simultaneously with the radial drawing of the metal. To facilitate the drawing, the metal may be annealed by the application of heat to the points 25 where the lugs are to be formed. The lugs C are formed by drawing the metal radially about a central opening. I thus form a hollow cylindrical lug, which may be internally 30 screw-threaded to receive a screw G for engaging and holding the inclosed socket-body in place. This form of lug is therefore of especial advantage, since it enables the use of screws for holding the socket-body without 35 requiring the use of the yokes or other separate devices employed in previous sockets to receive the screws.

While I have shown four sets of connecting devices, it will be understood that this 40 number is not essential and that the number of connecting devices may be varied as desired. For instance, the lugs E and the coöperating slots may be omitted and the lugs C and the coöperating slots D D' be relied 45 upon to hold the parts together, or the lugs C and the coöperating slots may be omitted and the lugs E and slots F F' be relied upon to

hold the parts together. In case only two sets of the connecting devices are employed the sets may be duplicates of each other or may 50 be of different forms.

It will be understood that the lugs C or E may be drawn radially inward or radially outward and that the lugs may be formed in either the cap or the shell, the coöperating slots being formed in the other part of the casing. It will also be understood that a part of the lugs may be formed in one part and a part of the slots in the other instead of forming all 60 of the lugs in one part and all of the slots in the other part, as shown in the drawings.

In the structure described the parts are held together at four points and are held rigidly together, so that they cannot sway or tip. The fastening devices do not depend upon 65 screws which will work loose under jarring and may be more cheaply made than the construction in common use.

What I claim, and desire to secure by Letters Patent, is—

1. A casing for incandescent-lamp sockets, consisting of telescoping shell and cap of sheet metal, one or more radially-extending integral cylindrical lugs on one part internally screw-threaded to receive body-holding screws, and a 75 slot or slots in the other part coöperating with said lug or lugs to hold the parts of the casing together.

2. A casing for incandescent-lamp sockets, consisting of telescoping shell and cap of sheet 80 metal, one or more radially-extending integral cylindrical lugs on one part internally screw-threaded to receive body-holding screws, one or more coöperating slots in the other part in combination with a locking device consisting 85 of a projection formed on one part and springing into a corresponding hole or slot in the other part.

In testimony whereof I have affixed my signature in presence of two witnesses.

NORMAN MARSHALL.
